ABSTRACT: A circuit interrupter of the vacuum type is adapted for reclosing operations and is utilized with a novel operating mechanism of simplified and easily accessible construction. The location of the vacuum interrupters in the high voltage compartment is remote from the operating mechanism and static control disposed in the low voltage compartment. The operating mechanism is of a simplified and of a low-cost construction incorporating a pair of supporting plates. The mounting of the reclosing mechanism and location of the main drive shaft results in an accessible and ultrasafe piece of interrupting equipment.

VACUUM CIRCUIT INTERRUPTER WITH HIGH VOLTAGE SWITCH COMPARTMENT AND LOW VOLTAGE OPERATING MECHANISM COMPARTMENT SEPARATED BY A GROUNDED METALLIC PARTITION

CROSS-REFERENCES TO RELATED APPLICATION

The present application is related to a copending patent application filed May 8 1968, Ser. No. 727,409 by Robert A. Few, which utilizes similar vacuum-interrupting units but a different mechanism.

BACKGROUND OF THE INVENTION

It is highly desirable to provide a vacuum-type circuit interrupter, particularly of the reclosing type, utilizing a simplified type of operating mechanism of low-cost construction. Additionally, it is desirable to provide the vacuum-interrupting units in a high voltage compartment, which is close to, but separated from, a low voltage compartment enclosing the operating mechanism, so that adjustments and maintenance may be carried out by service personnel without the presence of hazardous conditions.

In U.S. Pat. No. 2,858,395 issued Oct. 28, 1958 to A.R. Harm et al., there is disclosed and claimed a novel operating mechanism for a reclosing-type circuit interrupter. It is an additional purpose of the present invention to reduce the cost of the operating mechanism of the aforesaid patent, rendering it of reliable construction, and particularly adapting it for use with vacuum-type circuit-interrupting units, in which there is no need for oil to be used, as in the aforesaid Harm et al. U.S. Pat. No. 2,858,395.

Additionally, it is desirable to provide an improved operating mechanism, which provides shock-free operation of the butt-type contacts associated with the vacuum circuit interrupters, so that a relatively short travel may be utilized, and yet provision is made for preventing shattering of the contacts, and also for providing substantially simultaneous operation of the three vacuum-type interrupting units for the several phases.

SUMMARY OF THE INVENTION

In accordance with a particular aspect of the present invention, an operating mechanism of reduced cost is provided, which is associated with a high voltage interrupting compartment, in which are located the three pole units, each of which comprises a vacuum-type circuit-interrupting unit. The operating mechanism is, generally, of the type set forth in Harm et al., U.S. Pat. No. 2,858,395, but is modified to incorporate a pair of suitably configured and drilled spaced side metallic mounting plates of a construction adaptable for ready accessibility for service and maintenance. Additionally, a contact compression spring assembly is provided, associated with each of the three interrupting units, to prevent contact chattering, with the location of the high and low voltage compartments, such that maintenance may be carried on in a hazardous-free environment.

The general object of the present invention is the provision of an improved reclosing type of circuit interrupter particularly adaptable for the use with vacuum-type interrupting elements.

Still a further object of the present invention is the provision of a relatively cheap operating mechanism particularly adapted for use with a reclosing-type circuit interrupter.

Another object of the present invention is the provision of an improved reclosing-type circuit interrupter in which vacuum-type interrupting elements are accommodated.

Another object of the present invention is the provision of an improved operating mechanism for a vacuum-type circuit interrupter of relatively inexpensive construction, and easily adapted for adjustment and service operations, without subjecting operating personnel to hazardous conditions.

Still a further object of the present invention is the provision of a vacuum-type circuit interrupter of the reclosing type, in which the several elements are so located and positioned as to result in a highly compact construction. Further objects and advantages will readily become apparent upon reading the following specification, taken in conjunction with the drawings.

BRIEF DESCRIPTION OF THE DRAWINGS

FIG. 1 is a front elevational view of a vacuum-type circuit interrupter of the reclosing variety;

FIG. 2 is a side elevational view of the reclosing-type circuit interrupter of FIG. 1, the view being taken looking in at the left of the equipment in FIG. 1; spring-

FIG. 3 is a considerably enlarged view of the circuit interrupter of FIG. 1, taken generally along the line III—III of FIG. 1, illustrating the position of the several parts in the closed-circuit position;

FIG. 4 is a front elevational view, partially in fragment, and illustrating the general arrangement of the three vacuum-type pole units;

FIG. 5 is a side elevational view of the operating mechanism, drawn to an enlarged scale, and corresponding roughly to the mechanism outline of FIG. 3;

FIG. 6 is a fragmentary sectional view taken substantially along the line VI—VI of FIG. 5, the mechanism being illustrated in the closed-circuit position;

FIG. 7 is a front view of the operating mechanism of FIG. 5, the parts being illustrated in the closed-circuit position;

FIGS. 8 and 9 are front elevational and side sectional views of the main operating lever of the mechanism of FIGS. 5 and 7;

FIGS. 10 and 11 diagrammatically illustrate the operating mechanism of the present invention in the open trip-free position and the normally tripped position;

FIG. 12 is an enlarged sectional view of the contact compression spring assembly;

FIG. 13 is a side elevational view of one of the side mechanism support plates used in the improved operating mechanism of the present invention;

FIG. 14 is a block diagram of the static tripping circuit for the reclosing-type circuit interrupter of the present invention;

FIG. 15 is a top plan view of the grounded horizontal partition plate means;

FIG. 16 is a front elevational view of the low voltage compartment; and,

FIG. 17 is an enlarged side elevational view of the closing link or crank.

DESCRIPTION OF THE PREFERRED EMBODIMENT

With reference to the drawings, and more particularly to FIGS. 1 and 3 thereof, it will be noted that there is provided a circuit interrupter 1 of the reclosing type, incorporating a high voltage compartment, or housing 2, within which are three pole units, A B and C. Each pole unit incorporates a vacuum-type circuit-interrupting element 3 supported upon upstanding post-type insulators 4, 5 and adaptable for opening and closing operations by the provision of a suitable motor-driven operating mechanism, generally designated by the reference numeral 6, and illustrated more clearly in FIGS. 5-7 of the drawings.

With attention again directed to FIGS. 1 and 2, it will furthermore be noted that there is provided a low voltage compartment 7 disposed immediately below the high voltage interrupter housing 2, utilizing a hinged-type door 8 with an operating handle 9, the two compartments 2, 7 being supported by a supporting framework 10 including side metallic supporting panels 11, 12 mounted upon base structures 13, 14.

As well known by those skilled in the art, there are provided three pairs of terminal bushings 15-16, 17-18 and 19-20 associated with the three pole units A, B and C of the circuit interrupter 1.

FIG. 3 more clearly shows the general arrangement of a single pole unit A in relation to the main operating shaft 21 and the operating mechanism 6. It will be observed that the operating shaft 21 extends lengthwise of the low voltage compartment 7, and is operated by a crank arm 22, the free end of which is pivotally connected to a rod 23, carrying a spring seat 24, which compresses an opening accelerating compression spring 25 in the closed-circuit position of the interrupter 1, as illustrated in FIG. 3 of the drawings.

In other words, during the closing operation of the interrupter 1, a main operating lever 27 (FIGS. 8 and 9) is moved in a counterclockwise direction about its pivot 28 (FIG. 5) to force the operating rod 23, carrying the spring seat 24, toward the left, as viewed in FIG. 3, compressing the opening spring 25, and effecting clockwise rotation of the crank arm 22 affixed to the longitudinally extending main operating shaft 21. Fixed to the main operating shaft 21 are pairs of crank arms 29-31, which serve to operate contact-compression spring assemblies 33, the construction of which is more clearly illustrated in FIG. 12 of the drawings.

The vacuum-type interrupting units 3 may be of a type as set forth in U.S. Pat. application filed Sept. 30, 1969, Ser. No. 862,401 by Albert Bereza, and assigned to the assignee of the instant application. Generally, they are of a type in which a pair of separable butt contacts are separably engaged within an evacuated enclosure 34, one of the contacts being stationary and having a terminal rod portion 35 (FIG. 3), which is electrically connected by a flexible conductor 36 to the lower end of one of the two respective terminal bushings for the respective pole unit. The other cooperable contact 37 is movable, and is actuated through the intermediary of a cooperable pair of spaced rotatable bell-crank-shaped operating levers 38 pivotally mounted on a stationary pivot 39, the latter, in turn, being mounted on a U-shaped supporting bracket 40. As shown more clearly in FIGS. 3 and 4, the vacuum-type interrupting units, or elements 3 are mounted within the high voltage compartment 2 upon the upstanding spaced post-type insulators 4, 5.

OPERATING MECHANISM 6

The operating mechanism for effecting the rapid opening and closing operations of the contact structures 35, 37 is more clearly illustrated in FIGS. 3, 5-11 of the drawings. Generally, there is provided a framework 42 comprising two upstanding spaced metallic supporting plates 43, 44, the configuration of each of which is more clearly shown in FIG. 13 of the drawings. As shown in FIG. 5, which shows only one of the supporting plates 44, a releasably held operating lever 46 is pivotally mounted on a stationary pivot 47, the latter extending between, and supported by, the two upstanding side main support plates 43, 44. The upper end 46a of the releasably held operating lever 46 is pivotally connected, as at 48, to the main operating lever 27, which, in the closed-circuit position of the device 1, effects the compression of the opening accelerating spring 25, as heretofore described.

The main operating lever 27 is moved to its closed straightened position, as shown in FIG. 5, by the straightening of a single closing toggle, generally designated by the reference numeral 49, and comprising a pair of cooperable toggle links 49a, 49b, which are pivotally connected together by a knee pivot pin 49c. Also, pivotally secured to the aforesaid pivot pin 49c is a closing link 51, FIG. 17, the lower notched end 51a of which is engaged by a closing crank 52, which is secured to the shaft 53 of a worm gear 54, which is driven by a worm 55. In other words, the electrical closing of the recloser 1 is initiated by the closing of a switch, when energizes the motor circuit. The motor 57 drives the worm 55, which engages the worm gear 54. Directly secured on the shaft 53 of this worm gear 54 is mounted the closing crank 52 and the motor drum switch 58. As the shaft 53 rotates, the drum switch 58 seals in the motor circuit (not shown) so that the closing operation will be complete, even though the initiating switch (not shown) opens its closing contacts in the meantime. The crank 52 picks up the automatic closing link 51, which

moves upwardly, straightening the closing toggle 49 and effecting the closing of the several contacts 35, 37 within the vacuum interrupter units 3 through the linkage previously described. The closing toggle 49 is moved upwardly by the closing link 51 to an upward overcenter position, as shown in FIG. 5, against a stop 59. The motor 57 continues to drive the worm gear shaft 60 until the drum switch 58 opens the motor circuit.

Inasmuch as the closing crank 51 closes the recloser 1 simply by rotating 360° on the worm gear shaft 53, it is impossible to foul the mechanism 6 by tripping the recloser 1 during its operation. Regardless of the position in which the closing crank 51 may be stopped, or the position in which the automatic link may be held, on the next operation the closing crank 52 will simply rotate until it picks up the automatic link 51 again and closes the reclosing device 1.

As mentioned hereinbefore, the closing toggle 49 is not directly connected to the contacts of the vacuum units or to the motor 57 itself. The front end of the closing toggle 49 is supported by the latch lever 46, in turn fixedly positioned by a tripping toggle 62, while the rear end of the closing toggle 49 is connected to the linkage 27, 23, which compresses the main opening accelerating spring 25. The mechanism 6 is "cocked" or closed by applying the closing force to the closing toggle 49 in such a manner as to raise it upwardly and just overcenter to the stop 59. This forces the connected linkage to close the main contacts of the recloser, compressing the opening spring 25. The pressure of the opening spring 25 against the spring seat 24, fixedly secured to the operating link 23 (FIG. 3), holds the closing toggle 49 in the closed position by forcing it against the overcenter stop 59 until the breaker mechanism 6 is tripped. The closing force can be applied to the closing toggle either manually or automatically. As an operating handle is moved to the closed position, a roller on its linkage engages the manual closing link, which raises the closing toggle 49 to the closed position. The automatic link 51 performs the same operation when it is raised by the motor-driven closing crank 52, as described hereinbefore.

The latch lever 46 is releasably held by a rotatable latch 64, having a recess 64a therein, which accommodates a roller 46b pivotally secured to, and movable with, the latch lever 46. As shown in FIG. 5, the latch 64 is releasably maintained in the latching position by the latching toggle 62, the latter comprising a pair of latching toggle links 62a, 62b, pivotally connected together by a knee pivot pin 62c. A tension spring 65 biases the latch 64 to a reset position.

CONTACT COMPRESSION SPRING ASSEMBLY

To actuate the movable contacts 37 and to prevent shattering of the contacts, together with the provision of adequate contact pressure between the contacts in the closed-circuit position, there is provided a contact-compression spring assembly 33, more clearly illustrated in FIG. 12 of the drawings. With reference to FIG. 12, it will be noted that a tubular insulating operating rod 75 has pinned to the lower end thereof a cup-shaped member 76 having threadedly secured thereto a spring-guide rod 77. The spring-guide rod 77 has a sleeve 78 loosely mounted thereon, which extends interiorly of a compression-type contact spring 79. A movable spring seat 80, of generally cup-shaped configuration, is provided at the lower end of the contact compression spring 79 between the spring sleeve 78 and the head 81 of the spring-guide mounting bolt 77. In addition, the cup-shaped spring guide 80 has laterally extending therefrom a pair of trunnions 82, which extend through openings in a pair of spaced links 83, the intermediate portions of which are affixed to pins 84 movable at the free ends of the spaced actuating levers 29-31 welded to the main operating shaft 21.

The construction is such that upon rotation of the main drive shaft 21, the spaced pairs of driving crank arms 29, 30, 31 cause upward movement of the spaced pair of driving links 83 causing the several pivot pins 86 to move downwardly

within the slots 87 provided at the upper ends of the actuating links 83. This enables the contact compression springs 79 to be compressed, with the boltheads 81 moving downwardly through the cup-shaped spring seats 80. As a result, adequate contact pressure is achieved by the compression of the contact compression springs 79, and yet overtravel is permitted. Certain features of the contact compression spring assembly are described and claimed in U.S. Pat. application, filed May 8, 1968 Ser. No. 727,409 by Robert A. Few, and assigned to the assignee of the instant application.

FIGS. 3, 5 and 6 illustrate the position of the operating mechanism 6 in the completely closed-circuit position of recloser 1. It will be noted that the closing toggle 49 is in its overset position resting against the upper stop 59. The latch 64 engages the roller 46b of the latch lever 46 in its latched position, and the tripping toggle 62 is straightened, the tripping toggle links 62a, 62b being in an overcenter position. A shunt trip coil 88 (FIG. 5) is provided, which, when energized, effects upward movement of a plunger 88a which, in turn, effects clockwise rotation of a tripping lever 89. This will break the tripping toggle 62 permitting counterclockwise rotation of the latching lever 64 about its pivot 164 and release of the roller 46b permitting collapse of the closing toggle linkage, as illustrated more clearly in FIG. 10 of the drawings. It will be noted that in this trip-free position, even though the closing crank 52 has moved the closing link 51 upwardly, nevertheless the closing toggle linkage 49 is in an ineffective position due to the rotation of the floating pivot location 48 being as illustrated in FIG. 10 of the drawings. Due to the weight of the latching lever 46, and the provision of the resetting tension spring 65, the latch lever 46 and the latch 64, together with the tripping toggle 62, will be biased to a resetting position, as illustrated in FIG. 11 of the drawings. In the reset position, as illustrated in FIG. 11 of the drawings, an energization of the motor 57 will effect, through the worm 55, rotation of the worm gear 54 and closing movement of the crank arm 51. This will straighten the closing toggle 49 and effect closing of the circuit breaker 1, as described hereinbefore. A manually operable tripping rod 100 (FIG. 5) may also be provided.

STATIC CONTROL

FIG. 14 illustrates, in block diagrammatic manner, the static control supplied with the reclosing type of circuit interrupter 1. The circuitry of the static control is divided into the following five circuits:

1. Amplifier circuit.
2. Phase trip circuit.
3. Ground trip circuit.
4. Recloser timer circuit.
5. Reset timer circuit.

Each of these circuits is isolated on a plug-in, printed circuit board for ease of replacement.

The present invention is not concerned with the details of the static control, and reference may be made to U.S. Pat. application, filed June 5, 1962, Ser. No. 200,129, now U.S. Pat. No. 3,440,491, issued Apr. 22, 1966 to Nathaniel D. Tenenbaum and Gino J. Marieni, and assigned to the assignee of the instant application. Additionally, reference may be had to the circuitry providing a suitable time delay circuit, as set forth in U.S. Pat. application filed Feb. 28, 1968, Ser. No. 708,898 by Francis T. Thompson and likewise assigned to the assignee of the present application. Additional information is set forth in U.S. Pat. 3,105,920, issued Oct. 1, 1963 by Clyde G. Dewey, and U.S. Pat. No. 3,317,791, issued May 2, 1967 to Robert W. Price and Robert A. Few, the latter application being assigned to the assignee of the instant application.

As stated hereinbefore, the present invention is not concerned with the details of the static control, and only a general description thereof, as pertaining to the diagram of FIG. 14, will be included.

The primaries of the three current to voltage transformers for phase tripping are connected to the bushing current transformers. The secondary voltages are fed through full wave bridges and then connected in parallel. This parallel connection of the bridges results in a "maximum voltage network" which feeds the phase trip timing circuit. The voltage applied to the phase trip timing circuit is proportional to the magnitude of the fault current on any phase.

The secondary voltage on the ground transformer is also applied to a full wave bridge, filtered and rectified. The resulting DC voltage is applied to the ground trip timing circuit.

The phase and ground trip timing circuits feed a signal to the DC amplifier which in turn is connected to the trip circuit. The trip circuit is composed of a silicon-controlled rectifier to which the 24-volt battery is connected. Upon receiving a signal of the proper magnitude from the DC amplifier, the rectifier allows the battery voltage to be applied to the shunt trip coil, thus tripping the recloser.

The integrator is a stepping switch that is set to allow the recloser to interrupt and automatically reclose a predetermined number of times. The position of the integrator in its cycle determines whether the tripping sequence will be instantaneous or time delay. It also determines the length of the reclosing time to be used. These settings are made on the front panel of the control.

The reclosing timing circuit energizes an auxiliary-type SG relay which closes the motor circuit and allows the closing motor to operate. The reclosing time delay circuit is of the quick resetting type allowing the same circuit to be used for all reclosing intervals.

The reset timer is controlled by the integrator and the auxiliary switches of the reclosure. It operates every time this unit is closed but not prior to that time. It is also a quick resetting circuit which insures consistency of indicated timing values.

Each static-controlled recloser has included as standard equipment, facilities for three distinct time delay curves and two instantaneous curves for phase tripping. Also included is one instantaneous and one time delay curve for ground tripping.

A maximum and minimum value is shown for each time delay curve. The phase and ground curve adjusters allow adjustment of the curves between these limits. This feature allows closure system coordination.

The curves remain consistent as set within an accuracy of plus or minus 5 percent throughout the temperature range of -30° C. to +70° C. -22° F. to +158° F.).

A static control with three other time delay curves is available. The curves for this particular unit are described as extremely inverse compared to inverse for the standard static control. Curves for the extremely inverse control are adjustable between maximum and minimum limits in a manner similar to that for the standard control. The instantaneous phase trip curves and ground trip curves are not changed for the control with the extremely inverse time delay phase trip curves.

MECHANISM SUPPORT

The present invention is partly concerned with a novel fixed support for the operating mechanism 6. With reference to FIGS. 4 and 7, it will be noted that a pair of vertically arranged spaced side support plates 43, 44 are provided to fixedly secure the mechanism to a pair of T-shaped support blocks 72, and hence to a U-shaped channel member 26 secured, as by welding, to one of the three longitudinally extending cross support channels 32a, 32b and 32c, as more clearly shown in FIG. 4.

This provides a cost reduction feature and permits ready accessibility, together with a rigid mounting. Essentially, the mechanism is of the type set forth in the aforesaid Harm U.S. Pat. No. 3,030,471. Additional information is set forth in Baldwin U.S. Pat. No. 3,150,287, issued Sept. 22, 1964. By utilizing the pair of spaced vertically disposed metallic side

support plates 43, 44 and employing the pair of generally T-shaped supporting blocks 71 and 72 (FIG. 5) bolted to the side support plates 43, 44, and additionally secured by mounting bolts 78 (FIG. 4) to the upper support channel structure 26, ready accessibility and a desirable low-cost result is obtained.

COMPARTMENTALIZATION

The provision of a high voltage compartment 2 and a low voltage compartment 7 renders the reclosing device 1 electrically safe and free from hazardous conditions, as far as operating personnel are concerned. It will be observed that there is provided a horizontally extending apertured partition plate means 90, having apertures or holes 91 provided at the rear end thereof, as illustrated more clearly in FIG. 15 of the drawings. It will be noted that extending above the plane of the grounded apertured partition plate 90 are the insulating portions 75 of the operating-rod assemblies. In other words, all of the adjustments pertaining to the contact-compression spring assemblies 33 may be carried out below the level of the grounded partition plate means 90 by operating personnel. Additionally, all of the adjustments pertaining to the accelerating springs 25 (FIG. 3) and the mechanism 6 itself, together with the static control panel, may be performed in the low voltage compartment 7 thereby rendering an entirely safe construction.

From the foregoing description it will be apparent that there has been provided a static-controlled recloser of the three-phase type, which makes use of static components for all timing functions. The basic components of the recloser are a set of three gang-operated vacuum-type power interrupters 3, a set of three multiratio bushing current transformers for fault sensing, a powerful, heavy-duty accelerating spring 25 to supply the tripping power and a motor-operated closing mechanism 6, which also compresses the tripping spring.

In addition, a 24-volt, for example, direct current storage battery is provided to furnish control power to the static control and the shunt trip coil 88, with the static control performing all of the timing and integrating functions.

Up to 12,000 symmetrical amperes may be interrupted at a voltage rating of, for example, 14.4 kv. and X/R ratios up to 16. Instantaneous reclosing after the first tripping operation with no decrease in interrupting capacity may be provided or other times may be utilized. A 2½-cycle minimum total clearing time gives maximum protection with a direct motor closing having a closing time of 25 cycles.

Although there has been illustrated and described a specific structure, it is to be clearly understood that the same was merely for the purpose of illustration, and that changes and modifications may readily be made therein by those skilled in the art without departing from the spirit and scope of the invention.

I claim as my invention:

1. A circuit interrupter including metallic housing means defining a high voltage compartment, a plurality of pairs of terminal bushings extending downwardly into said high voltage compartment and supported by the upper cover thereof, a lower disposed metallic low voltage compartment enclosing a cooperating operating mechanism, interrupting means disposed in said upper disposed high voltage compartment and electrically connected to the lower ends of the pairs of terminal bushings, a grounded metallic partition plate interposed between the high and low voltage compartments, and linkage means interconnecting the cooperating operating mechanism with the several interrupting means.
2. The circuit interrupter combination of claim 1, wherein the grounded metallic partition plate has openings provided therein, and the linkage means extending through said openings to actuate the individual interrupting means.
3. The circuit interrupter combination of claim 2, wherein a contact spring assembly is provided for each interrupting means, said contact spring assembly including an insulating operating rod, and the region above the openings in the partition plate having only the insulating portion of the insulating operating rods extending thereabove.
4. The circuit interrupter combination of claim 1, wherein a longitudinally extending rotatable main operating shaft is provided rotatably mounted below the partition plate, and the linkage means is connected to said main operating shaft so that the several operating means are operated simultaneously.
5. The combination according to claim 4, wherein the longitudinally extending rotatable main operating shaft is disposed at the rear end of the low voltage compartment.
6. A circuit interrupter according to claim 1, including, quick-opening operating mechanism for a circuit interrupter having pair of spaced metallic side support plates, a main operating lever pivotally supported upon a pivot pin journaled in said two spaced metallic side support plates, means defining a closing toggle, means defining a releasable latch lever pivotally supported on the side support plates, the closing toggle comprising two pivotally connected toggle links and pivotally mounted to the main operating lever and also to the latch lever, a closing link connected to the knee pin of the closing toggle and picked up during the closing operation by a motor-operated closing crank arm, and a toggle-operated latch lever for at times under no tripping condition stationarily holding the releasable latch lever.
7. The operating mechanism combination of claim 6 wherein at least one T-shaped metallic support block spaces the sideplates and is adaptable for mounting to a stationary support.
8. The combination according to claim 6, wherein the pair of metallic side support plates is disposed vertically.
9. The combination according to claim 7, wherein two such T-shaped metallic support blocks are employed at the upper ends of the two side metallic support plates.
